UNITED STATES PATENT OFFICE.

CHARLES W. CUDLIPP AND PERCY S. PALMER, OF BRIDGEPORT, CONNECTICUT.

MIXING DEVICE.

Application filed May 16, 1922. Serial No. 561,522.

To all whom it may concern:

Be it known that we, CHARLES W. CUDLIPP and PERCY S. PALMER, citizens of the United States, and residents of Bridgeport, 5 county of Fairfield, State of Connecticut, have invented certain new and useful Improvements in Mixing Devices, of which the following is a specification.

Our invention relates to means for mixing 10 a liquid and a gas flowing together through a closed channel, the liquid being in the form of a spray or mist and carried by the gas. More particularly it relates to the mixing of liquid fuel and air in the manifold of internal combustion engines, between the carburetor and the engine.

As ordinarily carried out, the fuel supplied to an internal combustion engine is metered through a small orifice discharging 20 into the stream of air drawn through a carburetor and inlet pipe by the suction of the engine. Due to the velocity of the air current, the jet of liquid fuel is atomized and spreads out to a certain extent across the 25 area of the inlet pipe. A small portion of the liquid is vaporized, the percentage being in some proportion to the boiling point of the liquid fuel and the temperature of the incoming air. The greater portion of the 30 liquid fuel remains liquid, however, in the form of a mist or spray, and the action of the fuel and air may be likened to that of smoke issuing from a chimney in a high wind, where the smoke stream will proceed 35 for great distances without appreciably changing in form or size. It is well recognized that an intimate mixture of the fuel and air is very important in attaining regularity of operation and efficiency with internal 40 combustion engines. Much attention has been paid to the design of manifolds, inlet ports, and carburetors to effect this desired thorough mixture, and many schemes have been proposed to promote mixing by 45 providing at some point in the manifold devices such as screens, whirling fans, air bleeds and re-atomizers. The use of these devices is generally accompanied by either wear, hence short life, as with whirling devices, or throttling, as with screens which decrease the volumetric efficiency of the 50 engine at full load. In the case of air-bleeds the proportions of liquid fuel and air change, thereby impairing the fuel economy.

One object of our invention is to pro-

vide a cheap and efficient mixer, located between the carburetor and inlet ports of internal combustion engines, for obtaining a thorough mixture of fuel and air without restricting the flow of the mixture to 60 an appreciable extent. A further object is to provide a cheap and easily renewable combination mixer, gland and gasket, for performing the functions of mixing the fuel and air, for locating the manifold on the 65 engine block, and making the joint between the block and manifold tight. Other objects will appear from the detailed specification.

We attain these objects by constructing our mixer in part of thin sheet metal in 70 the form of a plurality of vanes extending across the current of air and fuel at an angle to the direction of flow. At all points throughout the length of the mixer, the total cross-section of air passage is approximately 75 the same. We usually employ two sets of such vanes for each mixer and one set may have its vanes extending in the same direction as those of the other or at angle to them. With some designs of manifold 80 it is desirable to use a plurality of mixers located at different points, to neutralize any tendency of the fuel and air to separate due to bends or other causes. By properly forming the two sets of vanes and assembling 85 them a combination gland and mixer may be produced and, furthermore, a yielding gasket may be incorporated in their construction.

In order that our invention may be readily 90 understood, it will be described in connection with the accompanying drawings, in which:—

Figure 1 is a side elevation of an engine block, manifold and carburetor showing how 95 our mixers are applied.

Figure 2 is a plan view of the parts of Figure 1 with the exhaust manifold cut off.

Figure 3 is an enlarged sectional view 100 of one of the mixers shown in Figure 1 and shows how it is constructed and applied between the cylinder block and inlet manifold to serve as a mixer, gland and gasket.

Figure 4 is a plan view of a mixer and gland showing a separate gasket.

Figure 5 is a section taken on line 5—5 of Figure 4.

Figure 6 is a sectional view of a modified 110 form of our combination mixer gland and gasket.

Figure 7 is a sectional view of a combined mixer and gasket having two sets of vanes and adapted for use between flanges.

Figure 8 is a plan view of a combined mixer and gasket for use between flanges and comprising a single set of vanes.

Figure 9 is a sectional view taken on lines 9-9 of Figure 8.

Figure 10 is a sectional view of a mixer similar to that of Figures 8 and 9, but having the vanes dished.

Figure 11 is a plan view of a simple form of mixer having one set of vanes and adapted for use in connection with the gland 15 of engines having manifolds of the type used on Ford engines.

Figure 12 is a sectional view taken on lines 12-12 of Figure 11.

Referring more particularly to the drawings, inlet manifold 1 is secured to the engine block 2 by studs 3, nuts 4 and yokes 5 (Figures 1 and 2) so that its openings correspond with the ports in the cylinder block. Carburetor 6 is attached to the manifold 1 by bolts 9 through flanges 7 and 8. A mixer 10 according to our invention is indicated as located between flanges 7 and 8. In some manifolds one mixer so located may be sufficient to thoroughly mix the fuel and air, so that it will enter the engine in proper condition, while in other cases we prefer to use additional mixers close to the ports as indicated at 11 and 12. When mixers are used at 11 and 12, that near the carburetor may be advantageously omitted where the design of the manifold is correct.

In Figure 3 a very satisfactory form of mixer is shown illustrating on a large scale those used at 11 and 12 (Figures 1 and 2). A cup-shaped member 13 is formed of sheet metal, preferably brass or copper, so as to have a cylindrical wall 14, a flat circular flange 15 and a flat bottom. A number of vanes 16 are pressed out of the flat bottom so as to form flat surfaces, with parallel edges, presented at an angle to the current of fuel and air in the manifold. The vanes of member 13 are disposed so as to deflect the air current toward a line across the center of the mixer, the arrow indicating the direction of flow. A member 17 is similarly formed to have a cylindrical wall 18 and a flange 19 turned back on itself to form a toroidal cavity 20 which is filled with suitable packing, such as asbestos. The vanes 21 in member 17 are disposed to alternately deflect the air current toward and away from a center line across the manifold. This, in effect, provides a series of alternately diverging and converging nozzles, each of substantially rectangular cross-section throughout its length, the total open area at all points being practically constant. The width of vanes 16 and 21 depend on their number and I have found, with a manifold one and one-eighth of an

inch in diameter, that six vanes give good results. The angle of the vanes to the direction of flow is important as if they are too steep they tend to throttle the engine. An angle of 45° is satisfactory when two sets of 70 vanes are used. Members 13 and 17, when formed, are assembled on cylindrical collar 22, the outside of which snugly fits the cylindrical portions 14 and 18. The assembled mixer is placed in the recess 23 of cylinder 75 block 2 and manifold 1 is put in place over cylindrical portion 14. Yokes 5 (Figures 1 and 2) are pulled down by bolts 3 and nuts 4 to tightly hold the manifold and compress the packing in cavity 20. It is to be noted that mixers 11 and 12 thus serve to properly locate the manifold.

In the embodiment of our invention shown in Figures 4 and 5, members 24 and 25 are alike and the vanes are arranged similarly 85 to vanes 21 of Figure 3. Cylindrical portions 26 are rolled into grooves, after assembly, formed in the outer surface of collar 27. A separate gasket 28 of the usual packing filled type is shown in connection with the 90 mixer. It will be observed that the outer vanes 29 are cut back to permit of their being turned to the desired angle and to restrict the flow as little as possible.

The vanes of the mixer illustrated in Figure 6 are arranged similarly to those of Figure 3. The flanges 32 and 33, however, represent one example of many possible constructions for holding the packing. Members 30 and 31 have in this example flat circular flanges 32 and 33, between which is placed packing 34. A ring 35 of U section is rolled over flanges 32 and 33 after members 30 and 31 are assembled on collar 36, to hold the mixer together.

In Figure 7, we have illustrated a form of mixer useful in connection with standard flanges having an outline of the shape shown in Figure 8. The vanes are similar to those of Figure 6. Collar 37 is cylindrical and fits inside of walls 38 and 39 of the vane elements. Sheet metal pieces 40 and 41 rest on flanges 42 and 43 and have packing 44 between them. Eyelets 45, with their ends flanged over, are provided at distances from the center corresponding to the bolt centers of the manifold and serve to hold the parts of the mixer together as well as to act as bolt-holes.

For purposes of illustration the mixers of Figures 1 to 7 have been shown with the two sets of vanes extending across the manifold in the same direction, but it will be readily understood that one set may extend in any direction in reference to the other.

A mixer comprising but one set of vanes is shown in Figures 8 and 9. Here the flat metal sheet 46 is of the form of a standard flange using two bolts and has vanes 47 formed in the center over an area corre-

sponding to the area of the manifold for which it is designed. Vanes 47 are shown as alternately deflecting fluid passing through them toward and away from a center line 5 through the manifold. When using a single set of vanes it is often desirable to have the angle they present to the current of air greater than when using two sets. Vanes 47 may be dished as illustrated in Figure 10 10 by dishing the sheet 46 before or at the same time the vanes are formed.

Figures 11 and 12 show a simple form of mixer adapted for use in connection with any pipe line in which it is desired to mix 15 and keep mixed a liquid in the form of spray and a gas. These may be put in at intervals as required between the two parts of any type of flange.

We claim:

20 1. A mixing device for air and atomized fuel, comprising two members, each member having a circumferential part adapted to be clamped between two port flanges and each member having a central part adapted 25 to span the port, said central part being formed into approximately chordal vanes presenting only inclined surfaces to the flow thru the port, the vanes of one member being at an angle to the vanes of the other member, 30 with yielding packing between the circumferential parts of the two members.

2. A mixing device for air and atomized

fuel, comprising two members, each member having a circumferential flange, a packing ring held between the two flanges, each of 35 said members having a central part within the flange formed into inclined chordal vanes, the vanes of one member being at an angle to the vanes of the other member, the combined action of both sets of vanes 40 tending towards a central delivery without rotative effect.

3. A mixing device for air and atomized fuel, comprising two members, each member having a circumferential flange, and a cylindrical centering gland portion, with a central port spanning part, having approximately chordal mixing vanes presenting only 45 inclined faces to the flow of gas and a yielding gasket between the said circumferential 50 flanges.

4. A mixing device for air and atomized fuel, comprising two members, each member having a circumferential flange, and a cylindrical centering gland portion, with a central port spanning part, having chordal 55 mixing vanes presenting only inclined faces to the flow of gas, the vanes of one member being set at an angle to those of the other member, and a yielding gasket between the 60 said circumferential flanges.
